UNITED STATES PATENT OFFICE.

ALBERT F. BANCROFT, OF WEST NEWTON, MASSACHUSETTS.

INSERTABLE PAD FOR SHOES.

Application filed January 5, 1928. Serial No. 244,625.

This invention relates to that class of foot supports which comprise a piece of somewhat yieldable and flexible material, or pad, usually made of rubber or leather and which is 5 adapted to be inserted in the shoe after it has been constructed.

The normal human foot, when pressed against a flat surface, only bears thereon in its shank portion at points near the outer side, 10 the width of the bearing surface of this portion relatively to the other portions being very narrow, particularly when no weight is being sustained thereon. While it has been attempted to manufacture shoes so 15 that the bottom thereof in this portion is correspondingly narrow, so that the upper adjacent thereto at the inner side will fit close to the longitudinal arch of the foot, as a practical matter, in the manufacture of 20 shoes by commonly employed methods, this cannot be done without increasing the manufacturing expense to an extent which is in most instances prohibitive. Consequently, the narrowest portion of the 25 shank part is usually made substantially wider than the corresponding portion of the foot which normally bears on a flat surface, so that the shoe does not fit as closely to the 30 foot as is desirable beneath its longitudinal arch, or at points which include the portions of the upper and shoe bottom adjacent the middle portion of the inner edge of the shank part. This difficulty may, to a large extent, 35 be overcome by cutting away the wood of the last along the inner edge of the shank, so that the inner-edge-portion of the shank part of the shoe would be correspondingly raised, but this would necessitate the use of right and left heels, or heels which are higher at the 40 inner side than at the outer side, and involve other difficulties which would increase the manufacturing expense to an extent which would be prohibitive in a medium grade shoe. The outer edge portion of the shank part may, 45 however, be made to fit closely to this portion of the foot without difficulty.

In the manufacture of certain shoes, special means are provided for supporting the transverse, or metatarsal arch of the foot, such 50 means usually consisting of a pad, or the like, which is either inserted between the inner and outer soles, or is in some way made a permanent part of the shoe. An objection of this type of shoe is that some persons either do 55 not require this additional support, or find

it objectionable, and, when the support cannot be removed or readjusted, a possible sale is lost as a result. However, in most instances, shoes provided with these additional supports are found to be desirable, so far as 60 comfort and fit is concerned, but the styles in which they are made by any one manufacturer are necessarily limited, so that the purchaser often has difficulty in finding these features in the style of shoe desired. That is, 65 shoes of the style desired may usually be found without difficulty, which do not also have the supporting features above referred to. Moreover, shoes having these special features are usually sold at a substantial increase 70 in price over similar shoes which do not have them.

The objects of my invention are to provide a form of filler piece, or pad, which, when correctly positioned in the shoe, will so fill the 75 space at the inner side of the shank part, or beneath the longitudinal arch of the foot, that the shoe will fit snugly to this portion of the foot, whether the weight of the wearer is, or is not being supported by the shoe bottom, and 80 which will at the same time afford a suitable and effective support for the transverse arch of the foot.

A further object is to provide means of this character which is adapted to be inserted in 85 a shoe after all manufacturing operations have been finished, except the insertion of a sock lining, or which may be placed in position in any shoe on partial displacement of the sock lining, and which, after it has been 90 placed in position, may be removed, or readjusted without difficulty. Also to provide a filler piece or pad which is so constructed that it may be satisfactorily positioned without difficulty on the bottoms of shoes of common construction, so that the purchaser, having found the style of shoe desired, may have it provided with the supporting features 95 above referred to at a small increase in expense.

I accomplish these objects by means of the construction hereinafter described and illustrated in the accompanying drawing in which:

Fig. 1 is a plan view showing the interior 105 of a shoe provided with a pad or filler piece embodying my invention.

Fig. 2 is a longitudinal section at approximately line 2—2 of Fig. 1.

Figs. 3, 4 and 5 are transverse sections 110

thereof at lines 3—3, 4—4, and 5—5, respectively of Fig. 1.

Figs. 6, 7 and 8 are bottom, top and edge views respectively of the filler piece.

5 Figs. 9 and 10 are cross sectional views at lines 9—9 and 10—10 of Fig. 7.

According to my invention I provide a filler piece, or pad *a*, preferably of soft, readily flexible molded rubber, which is 10 adapted to be placed within a shoe as *X*, in a predetermined position on its shank portion, the length of the pad being sufficient to extend from points adjacent the rear end of the shank part of the shoe to points slightly 15 beyond the front end of the shank part, or for a short distance on the forepart. The thickness of the pad is varied as hereinafter more particularly described, all thickened 20 portions being reduced to a thin edge, so that, when the pad is in position in the shoe and is covered by the ordinary sock lining, its interior will be practically smooth, or will have no objectionable unevenness.

The form of pad shown is designed for insertion in a right shoe, the form for a left shoe being opposite to that shown, as will be obvious, and its outline, starting from a nearly square corner *b*, at the inner edge of its rear end, comprises a curved rear edge *c* 25 which extends towards the front end as it extends laterally, an approximately straight longitudinal outer edge *d*, an approximately semi-circularly curved front end edge *e*, a nearly straight inner longitudinal edge *f*, 30 which is inclined inward at its rear end and is continued longitudinally a relatively short distance, providing an edge section *g* which extends to the corner *b*. The edge *g* is designed to coincide with a portion of the inner edge of the shoe shank, or innersole on 35 which the pad is to be placed, and the front end of the inner edge is designed to coincide with the inner edge of the inner sole at the ball, when the pad is correctly positioned in the shoe. A locating notch *h* is preferably 40 formed in the inner edge of the pad near its front end, so that, when the pad is to be placed in the shoe, as a part of a factory operation, previous to the insertion of the sock lining, 45 the pad may be correctly positioned on the inner sole by placing it in such a position that the notch *h* will register with similar notch as *y*, formed in the inner edge of the inner sole. Indicating means of this character 50 determines the longitudinal as well as the lateral position in which the pad is to be located, but the pad may be correctly positioned without serious difficulty if such means is not employed.

55 When held in this position, the inner edge portion of the pad will extend for a substantial distance up onto the inner side of the shoe upper, this portion being located beneath the longitudinal arch of the foot, and 60 the front end portion of the pad also will

be disposed adjacent the middle of the ball portion of the shoe, in position to support the metatarsal arch.

As indicated in the drawing, the bottom side of the pad is flat, and has a face *i* at its front end disposed at an obtuse angle to the rest of the surface, so that the face *i* meets the bottom surface in the rear thereof in a definite vertex line, as shown in Figs. 6 and 8. The top side of the pad is rounded transversely or is transversely convex from its front end nearly to its rear end, the extent of the convexity being gradually decreased from the front end rearwardly, being gradually flattened until its rear end portion becomes practically flat. The middle or highest point in the convex surface is at the middle of the pad at its front end, as indicated in Fig. 3, and what may be considered as the apex, or top of the convexity, gradually extends obliquely towards the inner edge, as indicated in Figs. 7 and 10, so that the thickest portion of the pad, at the middle part lengthwise, is adjacent the inner edge, as indicated in Fig. 9. That is, the surface is beveled much more sharply to the inner edge than to the outer edge, from the points of greatest thickness.

In practically all women's shoes which carry a high heel, the shoe bottom is constructed so that the inner surface of the shank part meets the inner surface of the forepart in a more or less well defined angular relation, the higher the heel the greater being the sharpness of the angle, and the angular relation between the main bottom surface of the pad and the front or beveled front end surface *i* is made to correspond approximately in angular relation to the average angularity of the shoe bottom above referred to. When the pad is placed in the shoe it will be so positioned on the shank portion thereof that the transverse vertex line formed where the bottom surface meets the front end surface *i* coincides as closely as possible with the vertex line between the shank and fore parts of the shoe. The end surface *i* will thus bear on the fore part surface, and the rest of the under surface of the pad will bear on the shank surface and the adjacent portion of the upper at the inner side of the shoe, the pad being bent to conform to the shoe bottom, so that the under side will be convex transversely, as indicated in Figs. 5 and 6, when in position in the shoe.

The pad will thus be positioned longitudinally of the shoe and will be correctly aligned therein, also the edge portion *g*, at the rear end portion of the inner edge of the pad will be placed, as nearly as possible, in coincidence with the inner edge of the inner sole, to position it transversely thereon, although other means for locating the transverse position may be employed.

As thus constructed and arranged the front

portion of the pad will provide a raised surface, which will fit into the portion of the foot beneath the transverse, or metatarsal arch, and provide a support therefor, while the rear portion will fill the space beneath the longitudinal arch, at which portion the shoe does not usually fit closely to the foot, as before described, so that the shoe will be made to fit the foot closely at this point, and will, incidentally, provide some support for the longitudinal arch of the foot.

As the outer edge portion of the shank part of the shoe may be, and usually is made to conform to the foot, the pad is not designed or intended to extend transversely to the outer edge of the shank part of the inner sole, but preferably terminates at a substantial distance therefrom, approximately as indicated in Figs. 3, 4 and 5. The pad is gradually tapered in thickness to a thin edge, both longitudinally rearward, and laterally to the side edges, so that a practically smooth bottom will be provided for the interior of the shoe after the sock lining has been cemented in position thereover. While the pad, will to some extent, act as a support for the longitudinal arch, it is not designed to have a corrective action on fallen arches, as it is of soft yieldable material, a primary purpose being so to form the interior of the shoe that it will fit closely to the portions of the foot, at which shoes, made by ordinary factory methods usually do not fit, and, at the same time, the pad provides an effective support for the metatarsal arch of the foot.

The above described form of pad may be correctly positioned in a shoe not provided with special arch supporting features as a part of the manufacturing operation, or may be later placed in position beneath the sock lining, the pad being pushed into the shoe until its front bottom surface engages the surface of the forepart as it extends from the shank part in angular relation thereto, in which position the transverse vertex line of the pad will approximately coincide with the vertex of the angular space between the shank and forepart of the shoe.

Where the pad is made for insertion in the shoes of a particular factory, the rear inner edge portion of the pad will also coincide exactly with the inner edge of the inner sole when the pad is in the correct lateral position, and this edge portion will also approximately coincide with the inner sole edge in practically any normal shoe, the pad in practice being made in sizes for insertion in a range of sizes and widths of shoes, and, when thus employed, may be correctly positioned without difficulty.

I claim:

1. An insertable filler pad for a shoe having the adjacent portions of the shank and forepart thereof disposed in definite angular relation, said pad being of soft, flexible ma-

terial and constructed to extend from the rear end portion of the shank part onto the rear end portion of the fore part of the shoe bottom and to extend laterally onto the portion of the upper adjacent the inner edge of the shank part, the shank engaging portion of the bottom surface of the pad being disposed obliquely to the bottom surface of the fore part engaging portion and meeting in a definite vortex line arranged to coincide with the vertex line of the angular space between the shank and fore part portions of the shoe when in position therein, and the top surface of the pad being transversely rounded and tapering to a thin edge at all points, for the purposes set forth.

2. An insertable filler pad for a shoe having the adjacent portions of the shank and forepart thereof disposed in definite angular relation, said pad being of soft, flexible material and constructed to extend from the rear end portion of the shank part onto the rear end portion of the fore part of the shoe bottom and to expand laterally from points adjacent and within the outer edge of the shank part onto a substantial portion of the upper adjacent the inner edge of the shank part, the bottom surface of the fore part-engaging portion of the pad being disposed at an angle to the bottom surface of its shank-engaging portion, forming a transverse vertex line arranged to coincide with the vertex of the angular space between the shank and forepart of the shoe, and the top surface being transversely rounded to a thin edge at each side edge and of gradually reduced thickness from said vertex line to a thin edge at the rear end, to fill the space between the shoe bottom and the transverse and longitudinal arches of the foot of the wearer.

3. An insertable filler pad for a shoe having the adjacent portions of the shank and forepart thereof disposed in definite angular relation, said pad being of soft, flexible material and constructed to extend from the rear end portion of the shank part onto the rear end portion of the fore part of the shoe bottom and to extend laterally onto the portion of the upper adjacent the inner edge of the shank part, the main portion of the bottom surface of the pad being initially flat and the bottom surface of the fore part engaging portion being obliquely disposed thereto, to form an angular portion adapted to fit the angular space between the shank and forepart portions of the shoe, and to position the pad longitudinally thereof, the rear end portion of the inner edge of the pad being arranged to coincide with the edge of the shoe inner sole, to indicate the proper lateral position of the pad thereon.

In testimony whereof, I have signed my name to this specification.

ALBERT F. BANCROFT.
